UNITED STATES PATENT OFFICE

161,063

COMBINED AUTOMOBILE TRANSPORT
TRUCK AND TRAILER

Clifford Brooks Stevens, Milwaukee, Wis.

Application September 8, 1950, Serial No. 12,111

Term of patent 14 years

(Cl. D14—3)

To all whom it may concern:

Be it known that I, Clifford Brooks Stevens, a citizen of the United States, residing at Milwaukee, in the county of Milwaukee and State of Wisconsin, have invented a new, original, and ornamental Design for a Combined Automobile Transport Truck and Trailer, of which the following is a specification, reference being had to the accompanying drawings, forming part thereof.

This application is a continuation-in-part of my copending application, Serial No. D. 869, filed February 15, 1949, now abandoned.

Fig. 1 is a front, side and top perspective view of the combined automobile transport truck and trailer, showing my new design; and

Fig. 2 is an enlarged rear perspective view thereof.

The side of the combined automobile transport truck and trailer opposite that shown in Fig. 1 is substantially the same as the side shown in Fig. 1. The characteristic features of my design reside in those parts shown in full lines.

I claim:

The ornamental design for a combined automobile transport truck and trailer, substantially as shown and described.

CLIFFORD BROOKS STEVENS.
